UNITED STATES PATENT OFFICE.

HARRY C. DOANE, OF BINGHAMTON, NEW YORK.

PORTABLE ELECTRIC LAMP.

1,266,427.

Specification of Letters Patent. Patented May 14, 1918.

Application filed January 4, 1916. Serial No. 70,160.

To all whom it may concern:

Be it known that I, HARRY C. DOANE, a citizen of the United States, residing at Binghamton, in the county of Broome and 5 State of New York, have invented new and useful Improvements in Portable Electric Lamps, of which the following is a specification.

This invention relates to portable electric 10 lamps and has for its primary object the provision of a structure, including a set of cells, which can be readily attached or detached from a vehicle, such as the dash board of a wagon.

15 Another object of the invention is the provision of a portable lamp wherein the lamp proper can be lowered or raised and can move in a horizontal plane to lie at any angle.

20 A further object of the invention is the construction of a cone shaped casing so that a portion of the light rays radiating from the reflector can be reflected rearwardly so as to illuminate a colored lens.

25 The invention consists in the features of construction, combination, and arrangement of parts, hereinafter fully described and claimed, reference being had to the accompanying drawings, in which:

30 Figure 1 is a front elevation of a wagon dash board showing the lamp applied thereto. Fig. 2 is a side elevation.

Fig. 3 is a vertical sectional view on line 3—3 of Fig. 2.

35 Fig. 4 is a vertical sectional view on line 4—4 of Fig. 1.

Fig. 5 is a detail view showing the parts forming the standards separated, and

40 Fig. 6 is a sectional view through a modified form of the invention.

Referring to the drawing, the numeral 1 designates the casing having an open end 3 closed by a sliding door 4. Positioned within the casing and electrically connected to 45 the binding posts 5 and 6 is a pair of cells 7 adapted to feed current to a circuit under the control of a switch 9 positioned upon the front of the casing, the casing being further provided with a handle 10 so that 50 the casing can be readily moved from place to place.

Secured to a central portion of the casing is a bracket 11 comprising a U-shaped frame 12 having its extremities bent back upon 55 themselves to form spaced limbs adapted to

contact with the opposite sides of a suitable support, such as a dash board 13.

Passing through one of the limbs and engaging the adjacent side of the dash board are thumb screws 14 whereby the bracket 60 can be rigidly secured to the dash board. At the front of the casing is provided an L-shaped bracket 15 having its horizontal portion provided with a vertical aperture 16 through which passes the threaded extremity 17 of a standard 18.

19 designates a nut engaging the threaded extremity of the standard whereby the latter may be rigidly held in any of its vertical adjustments. Also having connection with 70 the threaded extremity is a thumb nut 20 whereby the standard can be manually rotated.

The standard includes a pivotally connected bolt 21 having a threaded engagement 75 with a projection 22 carried by a cone shaped casing 23. This cone shaped casing has its small end provided with a colored lens 24 for projecting rearwardly a signal. The peripheral edge of the large end is 80 flanged as shown at 25 for a purpose herein-after described.

Secured within the cone-shaped casing in any suitable manner is a concave reflector 26 having a well known form of electric light 85 30 positioned in its focus. The inner terminal of the light contacts with a spring contact member 31 which is insulated from the casing 23 and which is connected to a wire 32. Current may flow from the cells 90 through the wire 32, spring contact 31, lamp 30, casing 23 and wire 32 back to the battery.

It will be seen that in this arrangement that the major portion of the light rays is 95 projected forwardly, while a small portion impinges upon the inner surface of the flange 25 so as to be projected rearwardly for illuminating the colored lens. By having the standard so formed, the lamp proper 100 can be elevated or lowered through its adjustable connection with the bracket, and can move vertically in an arc of a circle through the pivotal connection with the bolt 21 and can be rotated in a horizontal plane 105 through connection of the projection 22 with the bolt.

In the modified form I have shown the device without the inner concave reflector. In this figure, I support the electric light at 110

the small end of the cone shaped casing so as to leave an annular space 27 between the base of the electric light and the casing. The small end of the cone shaped casing is 5 further provided with a flared rim 28 in which is secured a colored lens 29. By constructing the device as shown in this figure, the colored lens can be illuminated by the indirect rays from the electric light passing 10 through the annular space.

What is claimed is:

A lamp including a frusto-conical casing, a lens mounted in the small end thereof, a reflector arranged in the casing, the edge of

the reflector of maximum diameter being 15 spaced from the wall of the casing, the edge of the casing in advance of the edge of the reflector being inturned, extended across the edge of the reflector and spaced therefrom, and a source of light arranged in the re- 20 flector.

In testimony whereof I affix my signature in presence of two witnesses.

HARRY C. DOANE.
